UNITED STATES PATENT OFFICE.

OTTO METZNER, OF CINCINNATI, OHIO, ASSIGNOR TO THE ROOKWOOD POTTERY COMPANY, OF CINCINNATI, OHIO, A CORPORATION OF OHIO.

TILE-COATING MACHINE.

1,093,064.

Specification of Letters Patent.

Patented Apr. 14, 1914.

Application filed September 16, 1912. Serial No. 720,454.

To all whom it may concern:

Be it known that I, OTTO METZNER, a citizen of the United States of America, and resident of Cincinnati, county of Hamilton, 5 ton, and State of Ohio, have invented certain new and useful Improvements in Tile-Coating Machines, of which the following is a specification.

This invention relates to tile coating apparatus and has for an object to produce an improved machine for distributing granular or powdered tile coating material over the faces of tile.

A further object is to produce an apparatus which is simpler in construction, more effective in operation and easier to operate and more rapid than machines now in use or known to me.

Various means are employed in the tile industry for coating the surfaces of tile with the material which forms the glaze after the tile are fired. The glazing material may be placed on the tile in a liquid or in a dry and powdered form; and this invention contemplates 25 a machine for evenly distributing a coating of granular or powdered glazing or coloring material across the faces of tiles. The dry glazing material is usually applied to the faces of the tile by hand or by means 30 of sieves, which are shaken over tile to be coated, in an endeavor to apply an even coating of the desired thickness to the faces of the tile. This method, however, is not accurate, since it largely depends on the individual skill of the operator, and it is even difficult for a skilful operative to cover each tile with the desired amount of coating material and to evenly distribute the material over the face of the tile.

40 One of the objects of this invention is to produce apparatus which, to a large extent, eliminates the possibility of errors on the part of the operatives, and which will deliver a desired amount of the coating material to each tile and spread it evenly over the face of the tile, even though the person operating the machine is not particularly skilful.

A further object is to produce a tile coating machine in which automatic means are employed for delivering definite and measured quantities of coating material to the distributer of the machine.

These and other objects I attain by means 55 of apparatus embodying the features herein

described, and illustrated in the drawings accompanying and forming a part of this application.

In the drawings, Figure 1 is a fragmental sectional elevation of a machine embodying my invention and illustrates the parts in the positions they occupy when the conveyer and the distributer are moved to the filling positions. Fig. 2 is a side elevation, on a reduced scale, of the machine shown in Fig. 1, portions being shown in section for convenience of illustration. Fig. 2 illustrates in full lines the positions the parts occupy during the operation of spreading the coating material over the tiles, and in broken lines the positions the parts occupy during the distributer filling operation. Fig. 3 is a fragmental perspective view of a distributer which forms a detail of the illustrated embodiment of my invention. Fig. 4 is a perspective view of a measuring and filling receptacle, which forms a detail of the illustrated apparatus, and is shown in connection with a fragmental perspective view of a portion of the conveyer frame and a receptacle returning hook or catch, which also forms a detail of the illustrated apparatus. Fig. 5 is a perspective view of the parts shown in Fig. 4, and illustrates the positions they occupy during the operation of filling the distributer.

The apparatus illustrated as an embodiment of my invention includes a support for tile during the coating operation, a distributer for spreading the coating material over the surface of the tile on the support, a movable conveyer on which the distributer is reciprocally mounted and which is capable of being moved from the coating or operative position to a filling position, in which the distributer is filled with a determined and measured amount of glazing or coating material. The apparatus also includes a measuring receptacle, which is automatically filled and which operates automatically to fill the distributer. A movable and automatically operated hopper is also provided, in the apparatus illustrated, for filling the measuring receptacle.

Referring more particularly to the drawings, by means of the reference numerals: The apparatus illustrated as an embodiment of my invention includes a swinging frame or conveyer 7, which is secured to the frame portion 8 of the machine, by means of

5 pivoted levers or links 9 and 10, in such a way that it is capable of being swung from an operative position on the front portion of the frame 8, as illustrated in full lines in Fig. 2, to a distributor filling position on the rear portion of the frame 8, as is illustrated in Fig. 1, and in the dotted lines in Fig. 2.

10 The conveyer 7, as illustrated, consists of a rectangular frame, which is provided with a screen or perforated sheet 11, preferably so mounted that its position on the conveyer, and its lateral tension may be varied as desired. In the apparatus illustrated, the 15 lateral edges of the screen are secured to longitudinally extending strips 12, each of which is located near one side of the conveyer 7, and is adjustably secured to the conveyer by means of bolts 13. The bolts 13 20 are shown as being provided with wing nuts and may be adjusted to move the strips 12 to different positions, with relation to the forward and rear edges of the conveyer, and to thereby vary the position of the 25 screen or vary its lateral tension.

30 An open bottomed distributor 14 is reciprocally mounted on the conveyer 7, and, as illustrated, consists of a rectangular frame, the internal longitudinal dimension 35 of which is substantially equal to the length of the screen. The distributor is so mounted, that it is capable of being moved laterally across the entire width of the screen, for the purpose of sifting the coating material, contained in it, through the screen. This is accomplished, in the illustrated apparatus, by mounting the distributor on reciprocally mounted rods 15 and 16, which are mounted in suitable bearings provided 40 on the conveyer. The inner ends of the rods 15 are rigidly secured to the forward lateral face of the distributor and the rods project forwardly, so that their outer ends extend beyond the forward edge of the conveyer. The forward ends of the rods 16 45 are rigidly mounted on the rear face of the distributor and the rods 16 extend rearwardly, with reference to the frame portion 8, and project beyond the rear face of the 50 conveyer. With this arrangement the rods 15 and 16 support and also guide the distributor, and it can be readily moved across the face of the screen 11 by moving the rods 15 back and forth. If desired, the forward 55 or projecting ends of the rods 15 may be provided with knobs or handles, as illustrated. The distributor is also provided with vibrators or rakes 17, which are adapted to bear against the screen, to aid in distributing the coating material across the 60 face of the screen and to vibrate the screen by contacting with its longitudinally extending wires. As illustrated, the vibrators 17 consist of comb-like members, which are 65 loosely mounted in longitudinally extend-

70 ing ways or slots 18, provided in the distributor adjacent to its lateral edges. Each vibrator is weighted and is so located that its teeth extend vertically and are held by the weight of the vibrator in contact with the face of the screen. The distributor is also provided with scrapers 19, which are so mounted on the exterior lateral faces of the distributor, that their lower edges yieldingly press upon the face of the screen. 75 As illustrated, each scraper consists of a flat metal strip and is secured to the distributor by means of screws, which extend through vertically extending slots provided in the strip. With this arrangement the 80 lower edges of the scrapers are held against the screen, and they operate to scrape the coating material across the face of the screen. The distributor is also provided with a longitudinally extending compartment 20, into which the coating material is placed, and from which it is delivered through the screen. The compartment 20 is of such length that it extends across the 85 entire length of the screen and it is located 90 centrally of the conveyer between the vibrators 17.

95 The apparatus illustrated is provided with a measuring receptacle 21, for delivering measured and determined quantities 100 of coating material to the compartment 20 of the distributor 14. As illustrated, the receptacle 21 is V-shaped in cross-section and is pivotally mounted on a shaft 22, which extends transversely of the apparatus, so that it is capable of tilting from an upright position, as shown in full lines in Fig. 2, to the dumping or delivering position, as shown in dotted lines in Fig. 2. The receptacle is provided with a downwardly extending finger 23, which is located below the shaft 22 in such a position that it is engaged by the conveyer, as the conveyer is moved back to the position shown in Fig. 1 and in dotted lines in Fig. 2. The finger 23, when so engaged, turns the receptacle about its mounting shaft to such a position that it falls forward by its own weight, and thereby delivers a charge 110 of the coating material to the distributor. Means are also provided for lifting the receptacle 21 back from the delivering position, as the conveyer is swung to the forward position on the frame 8. This is accomplished in the apparatus illustrated by 115 providing a laterally projecting lug 24, on the finger 23, and a latch or hook 25, on the conveyer frame 7. The lug 24 is so located with reference to the position of the hook 25 on the conveyer, that it moves upwardly 120 into the line of travel of the hook 25 as the finger 23 swings back in response to the pressure of the conveyer. With this arrangement, the hook 25 engages the lug 24, 125 as the conveyer is moved forward from 130

the filling position, and operates to swing the receptacle 21 back to the normal or upright position. A movable hopper 26 is provided on the machine for filling the receptacle 21 with the coating material, and then for leveling off the coating material contained in the receptacle, so that the receptacle always contains a definite and determined amount of the material.

10 The hopper 26 is open at the top and bottom, is located on the frame 8 below a supply box 27, and is adapted to move forward across a plate 28—from a position in which its upper end registers with an aperture 29 formed in the bottom of the box 27, to a position in which the lower end fits over the receptacle 21—when the conveyer 7 is moved from the rear to the forward position on the frame portion 8. The hopper is also 15 adapted to move back across the plate when the conveyer is moved back to the rear position on the frame. The hopper may be of any desired shape, but as illustrated it converges toward the lower end and is mounted on ways 30 provided on the frame portion 8. The conveyer actuates the hopper through the agency of a pair of links 34, each of which is pivotally connected to a separate post 35, rigidly mounted on the 20 conveyer. Each link is connected to the hopper by a lost motion connection, comprising a slot 36 formed in the link 34 and a pin 37 mounted on the hopper. The lost motion connections are so proportioned, 25 that, during the forward motion of the conveyer the hopper lags behind a sufficient amount to insure the moving of the receptacle 21 to the upright position, in which its rear edge engages and stands flush with 30 the forward edge of the plate 28. The lost motion connections are also so proportioned that the hopper is moved back across the plate 28, so that its bottom edges free the upper edges of the receptacle 21, before the 35 finger 23, of the receptacle, is engaged by the conveyer. As the hopper moves back across the plate the forward edge of the plate closes its lower end, and the forward edge of the hopper levels off the coating material contained in the receptacle, so that the receptacle is filled even with its upper edges. With this arrangement a determined and 40 definite amount of coating material is delivered to the receptacle each time the receptacle is filled, and consequently a determined amount of coating material is delivered to the distributer during each filling operation.

45 The operation of the apparatus is as follows: The conveyer 7 is moved back to the rear position for the purpose of filling the distributer 14. This is accomplished by moving the distributer laterally across the face of the distributer screen 11, until it 50 contacts with the rear edge of the conveyer,

and then by exerting sufficient pressure on a handle 7', with which the conveyer is provided, to swing the conveyer to the rear position. This is easily accomplished since the weight of the conveyer is counterbalanced by a weight 26, which is mounted on the link 10 and is capable of being moved to adjusted positions along the link. As the conveyer swings to the rear position on the frame 8, the hopper 26 is moved back along the plate 28 through the agency of the links 34. After the hopper is moved back past the forward edge of the plate 28 the rear face of the conveyer abuts against the finger 23 of the measuring receptacle and tilts the receptacle so that it falls forwardly, by its own weight, and delivers the coating material, contained in it, to the compartment 20 of the distributer. The conveyer is then swung to the forward position over the tile support by a pull on the handle 7'. As the conveyer moves to the forward position it first moves the receptacle to the upright position, and then moves the hopper 26 forward to the filling position, as has been described.

55 The receptacle 21 is so proportioned that it delivers pre-determined amounts of coating material to the distributer during each filling operation, and the area of the screen 11 is so proportioned, with reference to the size of the receptacle 21, that the coating material, delivered by the receptacle to the distributer, will cover an area, equal to the area of the screen, to a determined depth. 60 In addition to this the receptacle is provided with means for securing inserts or strips 39 in place within its interior for the purpose of reducing its interior volume, or its capacity for receiving coating material. 65 Each strip 39 is adapted to be secured to one of the inclined sides of the receptacle and is so formed that it extends the entire length of the receptacle and its upper edge is flush with the adjacent upper edge of the 70 receptacle. The inserts or strips 39 may be varied in thickness for the purpose of varying the amount of coating material which the receptacle will receive. This provides a simple and easy way of varying the thickness of the coating delivered by the distributer, since all that is necessary is to secure an insert of the desired thickness to the interior face of the receptacle, and the apparatus will operate automatically to 75 spread the amount of material delivered to it in even layers over the tile on the support.

80 During the coating operation tile are located on the tile support 38, which is located on the frame 8 below the forward position of the conveyer 7, and the distributer is moved laterally, first in one direction and then in the other, across the entire width of the screen. If this motion is maintained 85

substantially uniform, the distributor will deliver equal quantities of the coating material through equal sized portions of the screen; and consequently, will spread a coating of equal depth throughout the entire area covered by the screen. The tile located on the tile support receive the coating material as it falls from the distributor and consequently receive even coatings of glazing material. As has been said, the vibrators 17 cause a vibratory motion of the screen and consequently aid in the delivery of the coating material. The scrapers 19 also aid in forcing the material through the screen and they also confine the material between the lateral edges of the distributor, before it passes through the screen. In other words the scrapers 19 operate in conjunction with the vibrators to prevent a thin layer of the material from being distributed over, and resting upon the face of the screen.

During the tile coating operation the distributor operates to cover, with the coating material, an area, equal to the area of the screen, irrespective of the number of tile to be coated, and consequently, means must be provided for catching the material which falls past the tile located on the support. In the drawings a removable drawer 48 is provided for this purpose and is adapted to be mounted on a platform immediately below the tile support. Removable drawers 49 and 50 are also provided, which are respectively mounted below the receptacle 21 and the box 27 and are adapted to catch material, which may be accidentally spilled. All of the drawers may be removed for the purpose of pouring the material back into the box 27. After one set of tile are coated the conveyer is swung back to the distributor-filling position and the coated tile are removed from, and other tile are placed on the tile support, and the operation just described is repeated.

Under some operating conditions I find it necessary to provide means for preventing moist coating material from caking or stopping up the meshes of the screen. In the apparatus illustrated I have provided a heater 51, which is located on the frame portion 8, at a point immediately below that occupied by the screen, when the conveyer 7 is swung to the distributor filling position, as illustrated in Fig. 1. The heater heats the screen 11 and therefore aids in drying out the coating material, since the heat imparted to the screen is imparted to the material during the distributing operation, and consequently dries out the material and prevents it from clogging up the meshes of the screen. An electric heater is preferably employed and is so located and arranged that it will heat the entire screen and also permit the coating material which may drop from

the distributor to fall past it into the drawer 49. In the drawings I have illustrated an electric heater, each element of which is triangular in cross-section and is so arranged that the coating material cannot collect on the heater and impair its heating qualities. The terminals 52 of the heater illustrated may be connected to any suitable source of current supply. During the operation of coating tile, the conveyer is moved first to the distributing position over the tile support and then to the filling position over the heater, and consequently the heater is capable of keeping the screen hot and still does not interfere with the tile on the support or detrimentally affect the operation of the apparatus.

It will be understood that the machine illustrated may be employed for spreading equal layers of any kind of powdered or granular material, and that it may be employed in industries other than the tile industry. It will also be understood that coloring as well as glazing material may be applied to tile by the machine.

In accordance with the United States Patent statutes I have illustrated and described the preferred embodiment of my invention, but I desire it to be understood that various changes, modifications and substitutions may be made in the apparatus illustrated without departing from the spirit and scope of my invention as set forth in the appended claims.

What I claim is:

1. In an apparatus of the character described, a distributing screen for spreading coating material, a tile support located below the screen and an open bottomed receptacle for receiving coating material and for spreading it across the screen, said receptacle being movable across the screen.

2. In an apparatus of the character described, a movable conveyer, a distributing screen carried by the conveyer, a distributor movable across the screen and mounted on the conveyer, and means actuated by the conveyer for filling the distributor.

3. In an apparatus of the character described, a frame, a tile support mounted on the frame, a conveyer movably mounted on the frame and movable to a position over the support, a distributing screen mounted on the conveyer, a distributor mounted on the conveyer above the screen and provided with an open bottomed coating material receiving chamber, and means for moving the distributor across the screen.

4. In an apparatus of the character described, a tile support, a movable conveyer located above the support, a distributing screen mounted on the conveyer, a distributor mounted on the conveyer above the screen and movable thereacross and having a coating material receiving chamber formed

thereon, and means for guiding the motion of the distributer across the screen.

5. In an apparatus of the character described, a distributer having a coating material receiving chamber formed therein and extending longitudinally thereof, a receptacle adapted to dump a supply of coating material into the chamber, a screen substantially equal in width to the length of the chamber and proportioned in area to the capacity of the receptacle, such that the charge held by the receptacle will cover the screen to a predetermined depth, and means for moving the distributer across the face 10 of the screen.

6. In an apparatus of the character described, a tile support, a movable conveyer located above the support, a distributing screen mounted on the conveyer, a distributer 20 movably mounted on the conveyer above the screen and having a coating material receiving compartment formed therein and extending longitudinally thereof, and means for moving the distributer across the face 25 of the screen.

7. In an apparatus of the character described, a distributing screen, a distributer movable across the screen, an automatic measuring receptacle for filling the distributer, and an automatically actuated hopper for filling the receptacle.

8. In an apparatus of the character described, a tile support, a distributer movable across the support, a measuring receptacle 35 for filling the distributer, means for moving the distributer toward and away from the support and means, actuated by the first mentioned means, for actuating the receptacle to fill the distributer.

40 9. In an apparatus of the character described, a tile support, a distributer movable across the support, a measuring receptacle, a hopper for filling the receptacle, and means for moving the distributer to a position above the support and to a receptacle filling position, and means actuated thereby for actuating the receptacle to fill the distributer and for moving the hopper to fill the receptacle.

50 10. In an apparatus of the character described, the combination of a distributer with a measuring receptacle for delivering coating material thereto, and a removable insert for varying the capacity of the receptacle.

55 11. In combination with a distributer, a measuring receptacle for delivering coating material to the distributer, said receptacle being V-shaped in cross-sectional area, a removable insert for varying the capacity of the receptacle and means for securing the insert to an inclined side thereof.

60 12. In an apparatus of the character described, a distributing screen, a distributer, means for moving the distributer across the

screen and a comb with its teeth resting upon the screen and carried by the distributer across the screen to impart vibration thereto.

13. In an apparatus of the character described, a distributing screen, a distributer mounted above and movable across the screen and having a coating material compartment formed therein, and a vibrator mounted on the distributer for engaging the screen and for producing a vibratory motion thereof as the distributer is moved across the screen. 70

14. In an apparatus of the character described, a distributing screen, a distributer located above and movable across the screen and having a coating material receptacle formed therein, a vibrator actuated by the distributer in its movement across the screen, for causing a vibratory motion of the screen and a scraper carried by the distributer and yieldingly engaging the face of the screen. 80

15. In an apparatus of the character described, a frame, a tile support mounted on the frame, a distributer mounted on the frame above, and movable across, the support and having a coating material compartment formed therein, a measuring receptacle mounted on the frame and actuated by the motion of the distributer to deliver 90 coating material to the receptacle. 95

16. In an apparatus of the character described, a tile support, a conveyer movable to a position over the support, a distributer mounted on the conveyer, a pivotally mounted receptacle for filling the distributer engaged by, and moved to a delivering position by, the conveyer, and means for righting the receptacle. 100

17. A tile coating machine comprising, a tile support, a distributer movable across the support, a receptacle for filling the distributer, a hopper for filling the receptacle and a conveyer, on which the distributer is mounted, for actuating the receptacle and the hopper. 110

18. In a tile coating machine, a tile support, a conveyer movable to a position above the support, a distributer movably mounted on the conveyer, a measuring receptacle for filling the distributer, a movable hopper for filling the receptacle and means actuated by the conveyer for moving the hopper. 115

19. In combination in a tile coating machine, a tile support, a movable conveyer, a screen carried by the conveyer, a distributer mounted on the conveyer and movable across the screen, a movable receptacle actuated by the conveyer for filling the distributer, a movable hopper for filling the receptacle and means actuated by the conveyer for moving the hopper. 120

20. In combination in a tile coating machine, a tile support, a swinging conveyer 130

movable to a position above the support, a distributor mounted on the conveyer and movable across the support, a measuring receptacle for the distributor actuated by the 5 conveyer, a movable hopper for filling the receptacle and for leveling off the material contained therein and means actuated by the conveyer for moving the hopper.

21. In an apparatus of the character described, a receptacle for holding coating material, a tile support, a distributor movable from a point adjacent to the receptacle to a point above the tile support, a screen upon the bottom of the distributor, and a 15 heater located adjacent to the path of the distributor and at a distance from the tile support.

22. In combination in an apparatus of the class described, a frame, a tile support mounted on the frame, a heater mounted on the frame, a movable conveyer mounted on the frame and movable from a position over the tile support to a position over the heater, and a distributing screen mounted on the 25 conveyer.

23. In combination in an apparatus of the class described, a frame, a conveyer mounted on the frame and movable to a forward or distributing position and to a rear or filling position, a distributing screen on the conveyer, a tile support located on the frame below the forward position of the conveyer and a heater for the screen mounted on the frame below the rear position of the conveyer.

24. In an apparatus of the character described, a receptacle for holding coating material, a tile support, a distributor movable from a point adjacent to the receptacle to a 40 point above the tile support, a screen upon the bottom of the distributor, and a heater adjacent to the receptacle and in position to heat the screen when the distributor is adjacent to the receptacle.

45. 25. In an apparatus of the character described, a distributing screen for spreading coating material, a tile support located below the screen, an agitator in contact with the screen, means for moving the agitator 50 across the screen, and a heater for heating the screen.

26. In an apparatus of the character described, a distributing screen, a distributor movable across the screen and having a coating material compartment formed therein, and means located on each side of the compartment for causing a vibratory motion of the screen as the distributor is moved thereacross.

60 27. In an apparatus of the character described, a distributing screen, a distributor

movable across the screen and having a coating material compartment formed therein, vibrators for engaging the screen located on each side of the compartment and loosely 65 engaged by the distributor, and scrapers, for yieldingly engaging the face of the screen, secured to the distributor and located on each side of the vibrators.

28. In an apparatus of the character described, a frame, a tile support mounted on the frame, a conveyer movably mounted on the frame, located above the support and movable to a position over the support, a distributor screen mounted on the conveyer, 75 a distributor mounted on the conveyer above the screen and having a coating material receiving compartment formed therein, and means for moving the distributor across the screen, and the conveyer along the frame. 80

29. In an apparatus of the character described, a frame, a tile support mounted on the frame, a conveyer movably mounted on the frame and movable to a position over the support, a distributing screen mounted on 85 the conveyer, a distributor mounted on the frame above the screen and having a coating material compartment formed therein, a filling receptacle mounted on the frame for delivering coating material to the distributor, a movable hopper for delivering coating material to the filling receptacle, means for moving the distributor laterally across the conveyer, means for actuating the filling receptacle and means for moving the hopper. 95

30. In a machine of the character described, a frame, a tile support mounted on the frame, a conveyer mounted on the frame and capable of being swung to a position above the support and to a position back of 100 the support, a distributing screen mounted on the conveyer, a distributor mounted on the conveyer above the screen and having a coating material compartment formed therein, a tiltable filling receptacle for the 105 distributor pivotally mounted on the frame, and capable of being turned by the conveyer to a position for delivering filling material to the distributor compartment and of being turned to an upright position, a 110 hopper mounted on the frame and movable into register with the top of the receptacle when the receptacle is in an upright position, and means for moving the hopper into register with the receptacle after said receptacle has been moved to an upright position. 115
